Primary Examiner — Terry Wallace(74) *Attorney, Agent, or Firm* — Cook Alex Ltd.(57) **CLAIM**

The ornamental design for a container base, as shown and described.

DESCRIPTION

FIG. 1 is a front perspective view, from above, of the claimed design;

FIG. 2 is a rear perspective view, from beneath, of the claimed design;

FIG. 3 is a top plan view of the claimed design;

FIG. 4 is an underneath view of the claimed design;

FIG. 5 is a front view of the claimed design;

FIG. 6 is a rear view of the claimed design;

FIG. 7 is a left side view of the claimed design; and,

FIG. 8 is a right side view of the claimed design.
